APPARATUS FOR TESTING THE RESISTANCE
OF TEXTILE FABRIC TO ABRASION, FLEX-
ING, AND CREEPINGMyril C. Shaw, Stilton, N. J., assignor to Asbestos
Textile Institute, New Brunswick, N. J., an as-
sociation

Application February 27, 1953, Serial No. 339,333

4 Claims. (Cl. 73—159)

1

This invention relates to apparatus for testing resistance of textile fabric to abrasion, flexing and creasing. The invention has been found to be especially adapted for testing the wearability of asbestos textiles and other fabrics of the heavier grades.

The relative wearability of a textile reflects the extent to which such cloths may resist loss in strength and structure as a result of: (1) abrasion induced by foreign materials constantly or intermittently acting upon the surface of the cloth, (2) the wear resulting from two faces of the same or similar cloths rubbing against each other, and (3) a flexing action wherein the cloth may be periodically subjected to a creasing or folding action.

In asbestos safety clothing, draperies, and similar applications, all of the above factors are influential and frequently the most significant in the ultimate destruction of such textiles.

This invention provides for the application of the destructive actions of abrasion, flexing and creasing simultaneously and thereby provides a means of testing which simulates the service conditions encountered by fabric when used in clothing, draperies, etc.

Further objects, features and advantages of the invention will more fully appear from the following description, taken in connection with the accompanying drawings, in which:

Fig. 1 is an end elevation of the machine as viewed from the drive end;

Fig. 2 is a cross-sectional view taken along the line 2—2 of Fig. 1;

Fig. 3 is a fragmentary view on an enlarged scale showing further details of the means for holding the specimens being tested and of the means for securing the abrasive layer to the abrasive roll.

Fig. 4 is a perspective view showing further details of a typical clamping bar for securing the specimen to the carrying roll or cylinder.

Fig. 5 is a cross-sectional view taken at 5—5 of Fig. 1 showing further details of the journal mounting for the abrasive cylinder; and

Figs. 6, 7, 8 and 9 are schematic views showing successive positions of the test specimens during the operation of the machine.

In general the machine comprises (Fig. 1) two rolls such as the cylinders, designated in general as 1 and 2, rotatably journaled in end frames, designated in general as 3 and 4, in such manner that the surfaces of rotation of the rolls are parallel. The cylinder 1 serves to hold specimens or strips of material to be tested, designated

2

in general as S, and the cylinder 2 serves to hold and carry suitable abrasive material for abrading the material to be tested. The abrasive material is most conveniently provided in the form of sheets which are suitably secured around the periphery of cylinder 2 and in the present embodiment I have successfully used for this purpose No. 1 grade Carborundum cloth. In certain cases it may be desired to use as an abradent a strip of fabric of the same character as that being tested. Preferably the cylinder 1 is substantially larger than the cylinder 2 and in the embodiment of the invention which has been successfully operated and is herein disclosed the cylinder 1 is 6" in diameter and cylinder 2 is 2" in diameter.

The cylinders 1 and 2 are suitably driven in the same direction of rotation so that their surfaces move in opposite directions. The specimens are secured to cylinder 1 in such manner that when 10 the cylinder is rotated the specimens assume an open loop formation. The cylinders 1 and 2 are so disposed that the peripheral surface of the cylinder 1 and the peripheral abrasive surface on the cylinder 2 are spaced apart a minimum predetermined distance in accordance with the material to be tested, and for this purpose provision is made to adjust such spacing. I have found for relatively thick asbestos fabric and the like material this distance should be three times the 15 thickness of the material to be tested. In the preferred method of operation the loops of material to be tested are of such length that they extend outwardly from cylinder 1 a distance substantially greater than the diameter of cylinder 2 so that the forward face of the loop specimens will be brought into engagement with the abrasive surface and due to the opposite direction of travel of said surface the loops will become partially wrapped about cylinder 2 and thereafter 20 the loop will be progressively flattened and will be pulled through the limited space between rolls 1 and 2 to thereby positively crease the material.

Further details of the machine will now be described with particular reference to Figs. 1 and 2. 25 The end frames 3 and 4 are rigidly secured and extend upwardly from the base plate 10 and are held in parallel spaced apart relation by means of cross plates 11 and 12. The roll or abrasive cylinder 2 in the present embodiment comprises a shaft or axle member 13 whose outer ends are rotatably journaled in suitable bearings carried by the respective bearing blocks 14 and 15 which are slidably mounted in the end plates 3 and 4. These blocks are constructed in a similar manner 30 and therefore it will only be necessary to de-

scribe the mounting of the block 14. The block 14 has a sliding fit within an opening provided in the end frame 3 and carries pressed therein the outer race of an anti-friction bearing 16, the inner race of which receives the shaft end. The block 14 is yieldably held in a direction axially of the bearing by plates 17-18 disposed on opposite faces of the end frame 3 and held in position by means of screws, such as 19, and cooperating nuts, such as 20, a resilient member, such as spring 21, being interposed between the head of the screw and adjacent plate so as to permit a slight movement of the bearing block 14 out of the plane of the end frame 3 for purposes to be hereinafter described. The shaft 13 carries a plurality of cylinder sections, such as the three sections 22 and the section 22b, which are presently made of steel and are clamped together by means of nuts 23 and 24 threadingly engaging the shaft 13. The cylinder sections jointly form the length of the cylinder. Each of the cylinder sections except one of the end sections, designated 22b, is provided with a radially extending recess or groove 25 (Fig. 3) for receiving the inwardly turned opposite ends of a strip of abrasive material A and a locking key 26 which serves to wedge the ends of the abrasive strip in the recess and hold the said strip tightly in position around the periphery of the roller section. The recesses 25 of the respective roller sections 22 are preferably staggered so as to avoid having the slight gap of the abrasive at this point continuous from one end of the roll to the other. This provision also permits securing to the respective cylinders strips having different abrasive characteristics when this is deemed desirable. The cylinder section designated 22b is provided with an ungrooved surface so that its periphery is continuous and this section thereby presents a smooth metallic surface for purposes of comparative testing. This section may be slightly larger than the other sections so that its uncovered diameter may be approximately the same as the cover or diameter of the remaining sections.

The journal blocks 14 and 15 are provided with inwardly extending lugs 14' and 15' in vertical alignment with fixed lugs 3' and 4' carried by the respective end frames 3 and 4 and helical compression springs 27 and 28 interposed between the respectively cooperating pairs of lugs. These springs are sufficiently stiff so that the cylinder 2 will exert the desired pressure against the specimens being tested during normal operation but will yield upon abnormal pressure, such, for example, as if a test specimen should break and be deformed into a thickness greater than the space provided between the rolls. The slightly yieldable mounting of the journal blocks 14 and 15 will permit one end of the shaft 13 to be depressed more than the other when required.

Test specimen roll

The roll 1 preferably comprises a cylindrical shell 30 (Fig. 2), which in the present embodiment is made from well seasoned hard wood but which may be made from suitable plastic material, carrying rigidly secured at its opposite extremities ends 31 and 32 having rigidly formed therewith stub axles 33-34 rotatably mounted in suitable bearings 35-36 carried by journal blocks 37-38 mounted in the end frames 3 and 4 in such manner as to permit vertical movement but prevent horizontal movement axially of the cylinder 1 or horizontal movement in a transverse direction thereto. The journal blocks 37 and 38

are held in the desired vertical position by means of screws 39 and 40 threadingly engaged in portions of the end frames 3 and 4 and provided with suitable means, such as the finger wheels 41-42, by which they may be adjusted so as to support the journal blocks in the desired adjusted position. The journal blocks are locked downwardly against the supporting screws 39 and 40 by suitable means, such as the set screws 43 and 44. By this means the axis of the cylinder 1 may be set in the predetermined fixed position to provide the desired space between the cylinders 1 and 2 and to maintain the cylinders in parallel relationship.

15 The stub shaft 33 (Fig. 1) extends outwardly beyond the frame 3 and carries secured thereto a pulley 50 drivingly engaged by a belt 51 which is driven by a pulley 52 secured to the output shaft of a gear box 53 which is drivingly connected to an electric motor 54, which in the present embodiment serves as the motive means for driving the machine. The opposite stub shaft 34 (Fig. 2) extends outwardly beyond the frame 4 and carries secured thereto a sprocket wheel 25 55 in driving engagement with a chain 56 which in turn is in driving engagement with a sprocket wheel 57 secured to the corresponding outwardly extending end 58 of the axle 13 of cylinder 2. The chain 56 is somewhat longer than required to encompass the sprockets 55 and 57 and passes around an idler roller 59 which is journaled on an arm 60 whose lower end is pivotally supported in a shaft end 58 and whose outer end carries a weight 61. This arrangement keeps the chain tight while at the same time permitting such movement of the roller 1 upwardly and downwardly as required to obtain the predetermined position of the axis of rotation. It will be seen from this that the rollers 1 and 2 are rotated in the same direction and therefore their peripheral surfaces move in opposite directions.

Fastening means for test specimens

The cylindrical shell 30 of the roll 1 is provided with parallel axially extending grooves of such depth radially inwardly as to accommodate means for clamping the ends of test specimens below the surface of the cylinder. The device is adapted to support three specimens spaced equidistant around the periphery of the cylinder 1 and for this purpose three pairs of grooves are utilized. The pair of grooves illustrated in Fig. 3 being designated 62-63 and the grooves of each pair are spaced apart so as to hold the ends of the test specimen in circumferentially spaced apart relationship. As a means of securing the ends of the test specimens in these grooves clamp bars (Fig. 4), such as 64, are employed. These clamp bars are preferably cylindrical and are provided with a slot 65 extending therethrough. In the present embodiment these slots are about 2" long to accommodate specimen strips of this width and the over-all length of the bar is approximately 3". These bars are provided with holes extending therethrough spaced outwardly beyond the ends of the slots 65 for receiving screws, such as 66, whose heads are recessed below the surface of the bar. The ends of the strip of material to be tested are inserted in the slots 65 in the direction shown in Fig. 3 and thereafter the bars are secured in position by means of the screws 66 which serve to securely clamp the ends of the strip of material in position on the test specimen roll 1. It will be seen with reference to Fig. 3 that the roll bars permit the

specimen loop to be folded over without damage to the material being tested.

In the present embodiment the machine is adapted to accommodate four series of test specimens each comprising three (i. e., twelve in all) and therefore each of the grooves is of sufficient length to accommodate four of the clamp bars 64 in axial alignment.

Operation

With the machine constructed and arranged as above described the cylinders will be adjusted so that the space between the circumference of the cylinder 1 and the abrasive circumference of the cylinder 2 will be substantially equal to three times the thickness of the strips of material S. I have found that this is a satisfactory distance to accommodate the double thickness of the collapsed loops of material and the crease at the outer edge of the collapsed loops and serves to give the degree of abrasion, flexing and creasing desired. With the specimen loops secured in the position above described the operation is as follows, referring more particularly to Figs. 6-9, inclusive. In the position shown in Fig. 6 the specimens S1, S2 and S3 due to the manner in which they are mounted and the rotation of the carrying cylinder 1 assume open loop formations as indicated. In the position shown in Fig. 7, some 30° later in the cycle of operation, specimens S2 and S3 are still in fully flexed positions, due to centrifugal force, while specimen S1 is making positive contact with the abrasive medium on cylinder 2 and is being wrapped around the abrasive surface on cylinder 2. Little or no abrasion is effected at this point but as the cycle advances specimen S1 is tightly wrapped around the abrasive cylinder, as shown in Fig. 8, and is being abraded through the action of the abrading surface moving in the opposite direction to the path of travel of the specimen. As specimen 1 further advances to the position shown in Fig. 9 it is subjected to the final abrasive action and creasing prior to emergence with subsequent flexing and opening, as shown by the specimen S2 in Fig. 2, and thereafter the foregoing steps are repeated during each revolution of the cylinder. It will thus be seen that the material being tested first slaps against the abrading surface, is then dragged over this surface and creased and upon emerging from between the rolls flexes out into an open loop preparatory to a repetition of the same treatment. This continues for the duration of the test. I have obtained entirely satisfactory results, for example, by the use of a machine in which the cylinder 1 rotates at 100 R. P. M. and the cylinder 2 at 50 R. P. M. This means that the above described cycle takes place at the rate of 100 C. P. M. for the duration of the test. As above indicated, the present embodiment accommodates twelve specimens, nine of which will come in contact with an abrasive covering on the corresponding three cylinder sections and the remaining three specimens which come in contact with the smooth section 22b of the roll are reserved and represent the unabraded specimens which are utilized in the final evaluation.

According to the preferred procedure, three of the specimens working against the abrasive material and preferably comprised in one of the circumferential zones are run for one-half hour and then removed for measurement. Three additional specimens in another one of the circumferential zones are run for a total of one hour

and then removed, and the three remaining test specimens subjected to abrasion are run to the point of destruction or until a total lapsed time of 180 minutes has been consumed. The three specimens which are mounted to work over the smooth surface of the cylinder, wherein no or little abrasion is evidenced, are run for the full 180 minutes and serve to indicate the flexural strength of the specimens in this group.

- 10 Having thus described my invention with particularity with reference to the preferred apparatus, and having referred to some of the possible modifications thereof, it will be obvious to those skilled in the art, after understanding my invention, that other changes and modifications may be made without departing from the spirit and scope of my invention, and I aim in the appended claims to cover such changes and modifications as are within the scope of the invention.
- 15 20 What I claim is:
1. In a machine of the character described, the combination of a first rotatably mounted roll provided with a plurality of pairs of axially extending substantially parallel grooves, the grooves of each pair being spaced apart and the pairs being spaced apart circumferentially, means for securing within said grooves below the circumference of said roll respectively opposite ends of strips of material to be tested with the ends of each of said strips disposed in respective pairs of said grooves, whereby said strips may assume an open loop formation upon rotation of said first roll, a second rotatably mounted roll providing a surface of rotation substantially parallel to and in closely spaced relation to the surface of rotation of said first roll for carrying an abrasive surface against which said material is pressed, and means for rotating said rolls in the same direction.
- 25 30 35 40 45 50 55 60 65 70 75 2. In a machine of the character described, the combination of a first rotatably mounted roll provided with a plurality of pairs of axially extending substantially parallel grooves, the grooves of each pair being spaced apart and the pairs being spaced apart circumferentially, means for securing within said grooves below the circumference of said roll respectively opposite ends of strips of material to be tested with the ends of each of said strips disposed in respective pairs of said grooves, whereby said strips may assume an open loop formation upon rotation of said first roll, a second rotatably mounted roll providing a surface of rotation substantially parallel to the surface of rotation of said first roll for carrying an abrasive surface against which said material is pressed, and means for rotating said rolls in the same direction, said rolls being adjustably mounted to thereby provide for a predetermined spacing in accordance with the material being operated upon.
3. In a machine of the character described, the combination of a first rotatably mounted roll provided with a plurality of pairs of axially extending substantially parallel grooves, the grooves of each pair being spaced apart and the pairs being spaced apart circumferentially, means for securing within said grooves below the circumference of said roll respectively opposite ends of strips of material to be tested with the ends of each of said strips disposed in respective pairs of said grooves, whereby said strips may assume an open loop formation upon rotation of said first roll, said strip securing means including a plurality of clamping means disposed in longitudinal alignment in each groove for se-

curing a like plurality of corresponding ends of specimens in each groove, whereby said roll may accommodate a number of specimens equal to the product of the number of said pairs of grooves and the number of said clamping means, a second rotatably mounted roll providing a surface of rotation substantially parallel to the surface of rotation of said first roll for carrying an abrasive surface against which said material is pressed, and means for rotating said rolls in the same direction, said rolls being adjustably mounted to thereby provide for a predetermined spacing in accordance with the material being operated upon.

4. In a machine of the character described, the combination of a first rotatably mounted roll provided with a plurality of pairs of axially extending substantially parallel grooves, the grooves of each pair being spaced apart and the pairs being spaced apart circumferentially, clamp bars of a diameter less than the depth of said grooves for securing within said grooves below the circumference of said roll respectively op-

5
10

posite ends of strips of material to be tested with the ends of each of said strips disposed in respective pairs of said grooves, whereby said strips may assume an open loop formation upon rotation of said first roll, a second rotatably mounted roll provided with an abrasive surface of rotation substantially parallel to the surface of rotation of said first roll and in such predetermined spaced relation thereto that said material is pressed against said abrasive surface by said first roll, and means for rotating said rolls in the same direction.
